UNITED STATES PATENT OFFICE.

ARTHUR C. DAVIS, OF BIRMINGHAM, ALABAMA.

ADJUSTABLE SCAFFOLD.

1,111,824.

Specification of Letters Patent. Patented Sept. 29, 1914.

Application filed December 26, 1913. Serial No. 803,792.

To all whom it may concern:

Be it known that I, ARTHUR C. DAVIS, a citizen of the United States of America, residing at Birmingham, in the county of Jefferson and State of Alabama, have invented certain new and useful Improvements in Adjustable Scaffolds, of which the following is a specification:

My invention relates to adjustable scaffolding for use in connection with stacks, standpipes and like structures, and my object is to simplify and perfect the construction of the scaffolding itself and the means for adjusting it in the stack.

A further object of my invention is to design the scaffolding so that it is slightly concave, having its center, which supports the crane, raised above and so connected to the outer stack engaging rim member, that the weight of the crane and other parts on the raised center of the scaffold serves to expand and wedge the rim member into engagement with the inner wall of the stack, so that the greater the weight on the scaffold, the more securely it is held in position.

A further object of my invention is to perfect a novel means for raising and lowering the scaffolding to adjust it in the stack, the several ropes leading to the scaffold raising tackle being preferably spliced together and led to the hoisting drum.

A further object of my invention is to improve the manner of connecting the goose-neck pole to the scaffold so that it can be swung around freely without interfering with the hoisting cable which in my construction is not required to be passed through the pole.

My invention involves other novel details of construction and arrangements of parts which are hereinafter more particularly described and claimed, reference being had to the accompanying drawings, in which:

Figure 1 is a vertical sectional elevation through a standpipe showing the scaffolding and stack in vertical cross section and, for the sake of clearness, also showing the frame, by which the scaffold is supported when moved and its hoisting tackle partly in elevation and partly in section. Fig. 2 is a top plan view of Fig. 1 with the pole shown in cross section. Figs. 3 and 4 show partial plan and elevation views, respectively, of a part of the sectional grip rim. Figs. 5 and 6 are enlarged detail views show-

ing an elevation and a vertical sectional view through the grip rim. Fig. 7 is a detail plan view of the frame for supporting the scaffold when being raised or lowered. Fig. 8 is a detail elevation of the end cross member of the frame shown in Fig. 7. Fig. 9 is a cross sectional view of the pole taken on the line $x-x$ of Fig. 1. Fig. 10 is a detail view of the connection sleeve for joining together sections of the pole.

Similar reference numerals refer to similar parts throughout the drawings.

I have shown my invention in use in connection with a circular stack comprising sections 1 and 2, but it can obviously be adapted for use with stacks having other cross sectional shapes.

The scaffold proper comprises an annular peripheral grip rim formed of angle iron in arcuate sections 3, 4, 5 and 6, each of which sections is preferably a quadrant. The sections 4 and 5 and the sections 3 and 6 being connected together in pairs at their meeting edges by the plates 7, which plates are bolted to one rim section of each pair and either bolted or riveted to the other rim section of a pair. The meeting of the sections 5-6 and 3-4 are provided with plates 8 which are bolted to the top flanges of the sections so as to overhang the inner edge of the rim and they have opposing vertical flanges 9 near their inner edges which are provided with threaded alining openings to receive a screw 10 which is reversely threaded at its ends and provided with a nut 11 at its center by means of which it can be turned in either direction to draw the plates together or to force them apart, thereby expanding and contracting the rim. As will be seen by reference to Fig. 6, this rim has the outer face of its sections roughened by providing sharp outstanding spurs 12, which will increase its grip against the inner wall of the stack and will also assist in preventing any tendency of the scaffold to creep during operations.

I attach at intervals to the rim pairs of radially disposed connecting bars which at their outer ends engage the top and bottom face of the top flange of the rim and are fastened thereto by a bolt 16. These bars connect the rim to an inverted dish shaped central platform 13. Each pair of connecting bars comprise an upper flat bar 14 and a lower angle bar 15. The bars of each pair engage the inclined outer edge of the plat-

form 13 on both sides and are connected thereto by a bolt 17 which passes through an elongated slot 18 provided in the inclined outer edge of the platform 13. Wedges 19 are inserted at the inner ends of the slots 18 and bear against the inner ends of each pair of bars 14, 15. These bars are spaced apart, there being preferably two pairs for each rim section and they form a skeleton frame 5 adapted to support any suitable type of 10 flooring (not shown). I bolt to the under face of the platform 13, and concentric therewith, a flanged collar 20 having its flanged portion connected by countersunk 15 rivets to the plate 13. The depending collar portion is circular in cross section and has a vertically disposed round opening there-through concentric with a central opening in the platform 13. I clamp about this collar 20 a supporting frame for the scaffold when being adjusted which comprises two similar 20 reversely disposed bent metal bars which are provided with curved central portions 21 adapted to be fitted about the collar and to 25 be clamped thereto by the bolts 22. The other ends 23 of these bars engage the flange of the collar 20 and the outer edge of the 30 platform 13 from which point they are inclined downwardly and bent apart from 35 each other as shown more clearly in Fig. 7. To the outer ends of the bars I connect 40 plates 24 which have attached to their centers vertical eyes 25. These eyes, as shown in Fig. 1, are disposed between radial pairs 45 of bars 14, 15 so that a block and tackle 50 may be connected with each of them by a hook 27 and suspended by a hook 28 from an S-hook 29 that engages the top ring of the stack. The ropes 30, leading from the 55 two blocks and tackles, are spliced at 31 to a rope 32 which extends down through the stack to the hoisting machinery (not shown).

The goose-neck pole 33 has its lower end 60 fitted over and supported by a vertical pin 34 which is connected to or formed integral with a horizontally swinging plate 35, which is pivoted, at its inner end, by a down turned cylindrical tubular bearing 36 that 65 fits into and turns in the alining opening in the platform 13 and collar 20. A series of sheave wheels 37 are suitably connected by clamps 38 to the pole, the wheel on the vertical part of the pole being disposed with 70 their inner peripheries in alinement with the central opening in the bearing 36. A clamp 38 near the upper end of the pole has a rearwardly-extending lug 39 perforated to receive a ring 40. To this ring 40 I connect 75 two or more guy ropes 41 which spread apart and have connected to their lower ends hooks 42 that engage in the bolt-holes in the top section 2 of the stack. These guy ropes serve effectively to brace the pole. The 80 outer sheave wheel 37 is pivoted in the bifur-

cated end of the pole and a hoisting cable 43 is passed up through the center of platform 13 and about the wheels 37 and carries at its end the ordinary hook 44. The weight of the pole can be adjusted by the provision of 70 an intermediate section 45 which is shown connected above and below to the upper and lower sections of the pole by means of clamp sleeves 46 which are bolted about the abutting ends of the pole sections. 75

In operation, it will be noted that the pole 33 is free to swing with the pivoted plate 35 about the bearing 36 as a center so as to act on all sides of the stack and, as it is turned, the guy ropes 41 are adjusted about the stack 80 to properly brace it. After fastening the hooks 27 and 29 of each block and tackle to the top of the stack at one side and to an eye 25 of the supporting frame, the hoisting engine can be used to adjust the scaffold vertically to the desired point, the bars 23 engaging under and supporting the platform 13, and thereupon the screws 9 are turned to spread the rim sections into firm engagement with the inner wall of the stack. The 85 bolts 17 are loosened to permit the rim sections to move outwardly from the platform 13 and after the rim is in engagement with the stack, the wedges 19 are driven into the slots 18 and the bolts 17 tightened. Thereafter the pull on the block and tackles by 90 rope 32 can be released and as the weight of the pole and scaffold, the pull of the hoisting cable, comes on the central dish-shaped platform 13 the latter tends to give down and in 95 doing so acts with a toggle action, through the pairs connecting plates 14, 15, to wedge with greater tightness and security the outer rim against the stack. This wedging action makes the scaffold the tighter as the weight 100 on it increases. In order to again adjust the platform the reverse operation takes place. 105

It will be noted that the scaffold is so designed that it can be taken apart in the stack 110 and readily removed through the manhole in the bottom.

Without limiting myself to the specific details of construction hereinbefore pointed out, what I claim as new and desire to secure by Letters Patent, is:

1. In an adjustable scaffold, the combination of an expansible rim portion, a central platform, radial connections from the platform to the rim which are disposed at a 115 slight upward inclination from the rim to the platform, means to adjustably connect said radial connections to the platform, and a hoisting mechanism supported on said platform, substantially as described. 120

2. In an adjustable scaffold, an expansible sectional rim, radial connections adjustably connecting said rim to a central platform; a central platform normally supported by said connections above the rim, a hoisting appa- 125

radius mounted on said central platform, and means to lock said rim and platform in spaced relationship, said radial connections being arranged to cause the weight of the 5 central platform to force the rim against the surrounding stack as the platform is pressed down, substantially as described.

3. In an adjustable scaffold, a rim section 10 adapted to engage the inner wall of a stack, a central platform, hoisting mechanism supported on said platform, radially disposed members adjustably connecting the platform and rim sections, a supporting frame which is connected to the platform and projects 15 outwardly beyond same to a point adjacent to said rim, block and tackle adjustable connections for the outer ends of said frame from the stack, and a cable for operating said block and tackle connections from machinery on the ground, substantially as described.

4. An adjustable scaffold comprising a sectional rim, means to expand said rim against the stack, a central platform spaced 20 from the rim, radially disposed inclined connections between the rim and platform which are inclined so that the weight on the platform wedges the rim against the stack, said platform being of an inverted 25 dish-shape and having elongated radial slots about its edge, which slots receive adjustable fastenings for said radial connections, and hoisting mechanism supported centrally on said platform, substantially as described.

5. In an adjustable scaffold, in combination, a central platform having a vertical opening therein, a horizontally swinging member having a tubular bearing seated in 30 said central opening in the platform, a hoisting pole carried at the free end of said swinging member, sheave wheels, the wheel or wheels connected to the vertical base portion of said pole being disposed with pe-

ripheral edge or edges in vertical alignment with the center of the opening in the pivotal 45 bearing of said member, a hoisting cable which passes up through the openings in said platform and a member and passes over said sheave wheels, a rim, skeleton framework connecting said platform and rim, and 50 means to force the rim to clamp the inner wall of the stack, substantially as described.

6. In an adjustable scaffold, an inverted dish-shaped center platform having a flat 55 central top, a member pivoted at the center of the platform and adapted to swing in a horizontal plane, there being a vertical opening extending axially of said member through its pivot and said platform, a hoisting pole mounted on the free end of said 60 member, sheave wheels connected to the pole and a hoisting cable guided through said openings and over said sheave wheels, means to brace the upper end of said pole which are adapted to detachably engage the stack, 65 and an expandable rim section connected to and adapted to support said platform in the stack, substantially as described.

7. In an adjustable scaffold, an expandable rim, a central platform having a downwardly inclined peripheral edge in which are radially disposed slots, radial brace members each bolted at one end in one of said slots and connected at its other end to said rim, wedges inserted in the inner ends 70 of said slots and adapted to engage and force outwardly the inner ends of said members, and a hoisting mechanism supported on said platform, substantially as described.

In testimony whereof I affix my signature 75 in presence of two witnesses.

ARTHUR C. DAVIS.
